Application March 21, 1957, Serial No. 45,385

Term of patent 14 years

(Cl. D29—1)

FIG. 1

FIG. 2

FIG. 3

The appearance of the back of the Christmas tree ornament is substantially the same as that of the front.

I claim:

The ornament design for a Christmas tree ornament, as shown and described.
